UNITED STATES PATENT OFFICE.

DAYTON A. DUSENBERY, OF IONIA, KANSAS.

METHOD OF CONSTRUCTING CARTS.

1,301,410.

Specification of Letters Patent. Patented Apr. 22, 1919.

Original application filed December 31, 1917, Serial No. 209,669. Divided and this application filed September 4, 1918. Serial No. 252,603.

To all whom it may concern:

Be it known that I, DAYTON A. DUSENBERY, a citizen of the United States, residing at Ionia, in the county of Jewell and State 5 of Kansas, have invented certain new and useful Improvements in Methods of Constructing Carts, of which the following is a specification.

This invention relates to hand carts of 10 that general class shown and described in my copending application filed in the United States Patent Office on the 31st day of December 1917, under Serial No. 209,669, and of which the present application is a division.

The object of the invention is to provide a novel method of cutting the sides, handles and cleats of the cart from a single strip of material, whereby the units constituting the 20 body of the cart may be quickly formed and readily assembled without appreciable waste of material.

The method consists, generally stated, in forming spaced transverse incisions in the 25 intermediate portion of a blank or strip of material, connecting said transverse incisions by a plurality of longitudinal incisions directed obliquely to the longitudinal plane of the blank to form the sides, handles and 30 cleats, and subsequently detaching the units and assembling them to form the body of the cart.

Other and incidental objects will appear as the description proceeds. In the drawings wherein I have illustrated the preferred embodiment of the invention, and wherein similar reference characters designate corresponding parts throughout the several views:

40 Figure 1 is a plan view of a blank or strip of material from which the sides, handles and cleats of the body of the cart are constructed;

45 Fig. 2 is a perspective view showing the different units separated or detached;

Fig. 3 is a side elevation showing the parts assembled to form a cart;

Fig. 4 is a top plan view of Fig. 3.

Corresponding and like parts are referred 50 to in the following description and indicated in all the views of the drawings by the same reference characters.

In carrying out the method I provide an elongated blank or strip of material 5 having its opposite longitudinal edges 6 dis-

posed parallel with each other and its end walls 7 straight as shown. At the intermediate portion of the blank 5 I form spaced transverse incisions 8 extending inwardly from the opposite longitudinal edges 6 of the 60 blank to a point near the center thereof, the distance between the incisions 8 being preferably approximately twice the width of the blank. The inner end of one transverse incision 8 is connected with the intermediate 65 portion of the other incision by a longitudinal incision 9 disposed obliquely to the longitudinal plane of the blank to form the handle portions 10 of the cart, the outer ends 11 of the blank constituting the side 70 walls of the cart, as best shown in Fig. 3 of the drawings. Between the incisions 9 I form a plurality of other longitudinal incisions 12, preferably three in number, the material between the incisions 12 when divided along the line 13 constituting the vertical cleats 14 of the cart. Auxiliary incisions 15 are formed in the blank adjacent each transverse incision 8 and at an angle thereto, as best shown in Fig. 1 of the drawings, the substantially triangular strips of material 16 in the angles between the incisions 8 and 15, being the only waste material produced in the construction of the 75 body of the cart.

80 After the blank is cut in this manner and the several units thus formed separated, the lower edges of the handle portions 10 are concaved at 17 to form hand grips, after which the sides 11 are assembled in position 85 on the bottom 18 and secured in spaced relation by a transverse tie member 19. The cleats 14 are then secured to the inner faces of the side members 11 in spaced relation to form guides for the reception of the front 90 and rear walls 20 and 21, respectively, as best shown in Fig. 4 of the drawings. If desired the blank 5 may be of sufficient length to permit the front and rear walls 20 and 21 of the cart to be cut directly from the 95 opposite ends of the blank as will be readily understood. By laying off the blank in this manner and subsequently cutting the different units as described, the side walls, handles and cleats may all be cut from a single strip 100 of wood, or other material without appreciable waste of the material, the only material not used in the construction of the body of the cart being that portion in the angles between the incisions 8 and 15 as 110

previously stated. By making the distance between the transverse incisions 8 approximately twice the width of the blank 5, when the cleats 14 are severed on the line 13, said 5 cleats will be co-extensive in height with the side walls of the cart so as to properly fit said side walls and obviate the necessity of subsequently cutting or planing the ends of said cleats. It will, of course, be understood 10 that by varying the length and width of the blank the length and height of the cart may be correspondingly varied.

Having thus described the invention, what is claimed as new is:

- 15 1. The herein described method of cutting the sides, handles and cleats of a vehicle body from a single blank, which consists in forming spaced incisions in the intermediate portion of the blank and extending inwardly 20 from the opposite longitudinal edges thereof, and connecting said transverse incisions by a plurality of longitudinal incisions directed obliquely to the longitudinal plane of said blank.
- 25 2. The herein described method of cutting the sides, handles and cleats of a vehicle body from a single blank which consists in forming spaced transverse incisions in the intermediate portion of the blank and extending 30 inwardly from the opposite longitudinal edges thereof, with the distance between said incisions equal to approximately twice the width of the blank, and connecting said transverse incisions by a plurality of 35 longitudinal incisions directed obliquely to the longitudinal plane of said blank.
- 40 3. The herein described method of cutting the sides, handles and cleats of a vehicle body from a single blank which consists in forming 45 transverse incisions of equal length in the blank at opposite sides of the center thereof and extending inwardly from the opposite longitudinal edges of said blank, connecting the inner end of one transverse incision with the intermediate portion of the other incision by longitudinal incisions

disposed obliquely to the longitudinal plane of the blank, and forming a plurality of other longitudinal incisions in the blank between the first mentioned longitudinal incisions and parallel therewith.

4. The herein described method of cutting the sides, handles and cleats of a vehicle body from a single strip of material which consists in providing an elongated blank 55 having its opposite longitudinal edges disposed parallel with each other, forming spaced incisions in the intermediate portion of the blank and extending inwardly from the opposite longitudinal edges thereof, 60 with the distance between the transverse incisions equal to approximately twice the width of the blank, forming other incisions in the blank at an angle to the transverse incisions, and connecting said other incisions by a plurality of longitudinal incisions directed obliquely to the longitudinal plane of said blank.

5. The herein described method of forming the units constituting the body of a cart 70 and assembling said units which consists in providing an elongated blank having its opposite longitudinal edges parallel, forming transverse incisions in the intermediate portion of the blank and extending inwardly 75 from the opposite longitudinal edges thereof, connecting the inner end of one transverse incision with the intermediate portion of the other incision by longitudinal incisions disposed obliquely to the longitudinal 80 plane of the blank to form the sides and handle portions of the cart, forming a plurality of other longitudinal incisions in the blank between the first mentioned longitudinal incisions and parallel therewith, to 85 produce a series of cleats, cutting the cleats intermediate their ends and subsequently separating the units and assembling them to form the body of the cart.

In testimony whereof I affix my signature. 90

DAYTON A. DUSENBERY. [L. S.]
